UNITED STATES PATENT OFFICE

JOHN H. DAVIS, OF WATERTOWN, MASSACHUSETTS, ASSIGNOR TO RENAUD ET CIE. OF AMERICA, OF BOSTON, MASSACHUSETTS, A CORPORATION OF MASSACHUSETTS

DESIGN FOR A BOTTLE

Application filed May 23, 1931. Serial No. 39,949. Term of patent 14 years.

To all whom it may concern:

Be it known that I, JOHN H. DAVIS, a citizen of the United States, residing at Watertown, county of Middlesex, and State of Massachusetts, have invented a new, original, and ornamental Design for a Bottle, of which the following is a specification, reference being had to the accompanying drawing, forming part thereof.

The figure is a side elevation showing my new design for a bottle, the cross-section of which is circular.

I claim:

The ornamental design for a bottle, as shown and described.

JOHN H. DAVIS.
